FIG. II.

Patented Oct. 4, 1927.

1,644,647

UNITED STATES PATENT OFFICE.

AARON R. JONES, OF MILLVILLE, NEW JERSEY, ASSIGNOR TO MILLVILLE MANUFACTURING COMPANY, OF MILLVILLE, NEW JERSEY, A CORPORATION OF NEW JERSEY.

STOP MOTION FOR LOOMS.

Application filed May 15, 1926. Serial No. 109,212.

This invention relates to looms, more particularly to the type known as "automatic" looms which are characterized by mechanism for automatically replenishing the filling in the shuttles in the event of exhaustion of a bobbin or breakage of the filling. In such looms, one or more forked detectors are usually employed, these, by cooperation with grids on the lay, governing actuation 10 of the replenishing mechanism whereby bobbin substitution is effected; and interposed means are also provided to automatically trip the stop mechanism of the loom if mis-threading should occur incidental to two 15 or three successive bobbin replacements. A loom of the kind briefly described will, therefore, continue in operation so long as the grids are occupied by the filling thread. But, it will be seen that other obstructions 20 before the grid, such for example as accumulations of lint (ordinarily known as "fly") will also maintain the loom in action notwithstanding the absence of the filling.

The main object of the present invention 25 is to provide for automatic stoppage of the loom in the event of the contingency just noted, and to enable this to be accomplished without affecting the bobbin replenishing mechanism; or, in other words, without 30 tailing several substitutions of bobbins before the loom is actually stopped.

A further object of my invention is to attain the above desideratum in a very simple and inexpensive means having the form 35 of an attachment capable of being applied to existent looms without necessitating any alterations either in their construction or normal mode of operation.

In the drawings I have shown my invention 40 embodied in an automatic loom of the type disclosed in U. S. Patent No. 789,291, granted to Jonas Northrop under date of May 9, 1905, Fig. I being a fragmentary plan view of the loom corresponding to Fig. 45 I of the patent with portions broken away and in section to better illustrate certain important details which would otherwise be hidden.

Fig. II is a staggered sectional view taken 50 as indicated by the arrowed line II-II in Fig. I.

Fig. III is a view similar to the preceding illustration showing some of the parts differently positioned; and,

55 Fig. IV is a fragmentary detail plan view

taken as indicated by the arrows IV-IV in Fig. III.

With reference to the drawings, 10 designates the lay of the loom which carries the reed 11 and moves toward and away from the breast beam 12 in the performance of its usual function. At opposite ends, the lay 10 supports the boxes 13, 14 between which the shuttle 15 is thrown back and forth to draw the filling thread across the face of the reed 11. Mounted on the lay 10 adjacent the inner ends of the shuttle boxes 13, 14, are the grids 16, 17 that cooperate respectively with the forks 18, 19 of the main and auxiliary detector devices 20, 21 supported by the breast beam 12 previously referred to. The auxiliary detector device 21 is not especially concerned with the present invention and will not therefore be further referred to herein. The filling fork 18 of the main detector device 20 is pivoted at 22 between the side bars of a slide 23 that has capacity for horizontal reciprocation in a guide 24 bolted to the breast beam 12. The filling fork 18 has a rearwardly projecting tail loop 25 adapted to cooperate with a hooked element 26 pivoted to an actuator 27 which is constantly vibrated through suitable connections (not shown) with the cam shaft of the loom. 75

From Fig. II it will be observed that the element 26 has two hooks marked 28, 29 occupying different vertical planes, the lower hook being slidably supported on a cross bar 30 of the slide 23. Normally the filling fork 18 is shifted to the full line position of Fig. II when filling is present before the grid 16 on the lay 10; but in the absence of the filling, said fork will assume the dot-and-dash line position in Fig. II as a consequence of which its tail loop 25 will engage the lower hook 28 of the element 26 as the actuator 27 moves forward. When such engagement takes place, the slide 23 is carried forward by the actuator 27 in 100 opposition to the action of a leaf spring 31 (Fig. II), and the imparted motion transmitted, through an arm 32 in the path of said slide, to the rock shaft 33 which operates the filling replenishment mechanism 95 whereof a portion is shown at 34 in Fig. I. As a result of the actuation of the mechanism 34, a new bobbin B is placed in the shuttle 15 in the well known manner.

For the purpose of determining several actu-

ations of the filling replenishing mechanism before the loom is brought to a stop, a latch carrier 35 is provided, the same having a series of depending lugs which cooperate successively with corresponding notches in the slide 23 when the latter is moved while the latch carrier 35 is temporarily detained against longitudinal movement, all as described in the patent hereinbefore referred to. In addition to the depending lugs mentioned, the latch carrier 35 is equipped at one side with a special lug 36, which, after several successive actuations of the slide 23, takes a position to the front (left side in Fig. II) of the inner extremity of the knock-off lever 37 pivoted at 38 to the breast beam 12. The opposite extremity 39 of the knock-off lever 37 engages the belt shipper handle 40 which is normally held locked in a lateral recess 41 of its slotted holding plate 42. Thus on the last actuation of the slide 23, the special lug 36 of the latch carrier 35 will function to throw the knock-off lever 37 and thereby release the shipper handle 40 to stop the loom.

Thus far I have described the normal operation of a standard loom capable of effecting automatic bobbin substitution consequent upon failure of the filling thread through exhaustion of a previous bobbin B in the shuttle, or for any other reason. As hereinbefore pointed out, the purpose of my invention is to effect automatic stoppage of the loom through tripping of the belt shipper handle 40 in the event of abnormal obstruction such as lint or "fly" (as it is generally termed) before the grid 16 on the lay 10, but without necessitating the successive actuations of the filling replenishing mechanism 34, as above described. This function is vested in a thrust bar 45 which normally occupies the oblique position shown in Figs. II and III and it is limited in its longitudinal movement by a supporting stud 46 engaging through a slot 47 therein, said stud projecting laterally from a small bracket 48 attached by screws to the guide 24 at one side. The tail of the thrust bar 45 rests upon the knock-off lever 37 and is undercut as at 49 for cooperative engagement with the latter. The inner end of the thrust bar 45 is recessed somewhat as at 50, and lies closely contiguous to the upper hook 29 of the element 26, as shown to best advantage in Figs. I and IV. With special reference to Figs. III and IV it will be observed that when the cross bar of the tail loop 25 on the filling fork 18 becomes lodged in the upper hook 29 of the element 26 in consequence of an abnormal obstruction before the cooperating grid 16 on the lay 10, it is supported in a position in readiness to enter the recess 50 of the thrust bar 45. As a result, the thrust bar 45 will be obliged to follow the succeeding forward movement

of the slide 23, and, in so doing, will communicate its movement direct to the knock-off lever 37 thereby to dislodge the belt shipper handle 40 from the lateral notch 41 of the slot in the holding plate 42 and automatically stop the loom without entailing actuation of the filling replenishing mechanism 34. In this way I not only avoid waste of time and annoyance, but prevent losses attendant upon imperfections in the fabric being woven.

Having thus described my invention, I claim:

1. In an automatic loom comprising filling replenishing mechanism, a belt shipper handle, a filling detector cooperative with a grid on the lay, and interposed means determining successive operations of the filling replenishing mechanism previous to tripping of the belt shipper to stop the loom, the combination of thrust means carried by the loom breast beam and operative to trip the belt shipper handle in the event of an abnormal obstruction other than the filling before the grid without entailing actuation of the filling replenishing mechanism aforesaid.

2. In an automatic loom comprising filling replenishing mechanism, a belt shipper handle, a filling detector cooperative with a grid on the lay, and interposed means determining successive operations of the filling replenishing mechanism previous to tripping of the belt shipper to stop the loom, the combination of a thrust member carried by the breast beam and adapted to be actuated by the tail of the filling detector when moved to an abnormal extent in the event of an abnormal obstruction other than the filling before the grid to trip the belt shipper handle without entailing actuation of the filling replenishing mechanism.

3. In an automatic loom comprising filling replenishing mechanism, a belt shipper handle, and a pivoted filling detector cooperative with the grid on the lay, the combination of a shiftable element with hooks in different planes to respectively engage the bail of the detector in the absence of filling before the grid and when said detector is swung to an abnormal extent due to presence of an obstruction larger than the filling before the grid, and a thrust bar lying in the path of the tail of the detector when in the abnormal position and adapted to trip the belt shipper handle without entailing actuation of the filling replenishing mechanism.

4. In an automatic loom comprising filling replenishing mechanism, a pivoted filling detector cooperative with the grid on the lay, a vibrating actuator with a hook element adapted to engage with the bail of the detector in absence of the filling before the grid and also when said detector is

swung to an abnormal extent by an obstruction larger than the filling before the grid, a belt shipper handle, and means determining successive operations of the filling 5 replenishing mechanism previous to tripping of the belt shipper to stop the loom, the combination of a thrust bar carried by the loom breast beam and operative, when the detector is swung to the abnormal extent as aforesaid, to trip the belt shipper handle without entailing actuation of the 10 filling replenishing mechanism.

5. In an automatic loom comprising filling replenishing mechanism, a pivoted filling 15 detector cooperative with the grid on the lay, a vibrating actuator with an element having hooks in different planes to en-

gage the tail of the detector in the absence of filling before the grid and also in the event of an abnormal obstruction before 20 said grid, a belt shipper handle, and means determining successive operation of the filling replenishing mechanism previous to tripping of the belt to stop the loom, the combination of means adapted to be engaged by the tail of the detector, when 25 swung to an abnormal extent, to trip the belt shipper handle without entailing actuation of the filling replenishing mechanism.

In testimony whereof, I have hereunto 30 signed my name at Millville, New Jersey, this seventh day of May, 1926.

AARON R. JONES.
